US0D1014517S

(12) **United States Design Patent** (10) Patent No.: **US D1,014,517 S**
(45) Date of Patent: ** Feb. 13, 2024

(54) **DISPLAY SCREEN OR PORTION THEREOF WITH GRAPHICAL USER INTERFACE**

(71) Applicant: **Fisher & Paykel Healthcare Limited**, Auckland (NZ)

(72) Inventors: **David Martin Russell**, Auckland (NZ); **Anton Kim Gulley**, Auckland (NZ); **Hamish Chan**, Auckland (NZ); **Robert Stuart Kirton**, Auckland (NZ); **Christopher Harding Campbell**, Auckland (NZ); **Benjamin Wilson Casse**, Auckland (NZ); **Kevin Peter O'Donnell**, Auckland (NZ); **James Alexander Michael Revie**, Auckland (NZ)

(73) Assignee: **Fisher & Paykel Healthcare Limited**, Auckland (NZ)

(**) Term: **15 Years**

(21) Appl. No.: **29/788,343**

(22) Filed: **May 5, 2021**

(51) LOC (14) Cl. **14-04**

(52) U.S. Cl.

USPC **D14/492**; D14/486

(58) Field of Classification Search

USPC D14/485-495

CPC A61B 5/02; G06F 3/0481; G06F 3/0486

See application file for complete search history.
